REGISTERING AND CLAMPING MECHANISM

Henry A. Wise Wood, New York, and Perry R. Long, Larchmont, N. Y., assignors to The Wood Newspaper Machinery Corporation, New York, N. Y., a corporation of Virginia

Application June 4, 1936, Serial No. 83,424

18 Claims. (Cl. 101—378)

The present invention relates to means for insuring proper register of printing plates in multi-color presses.

In a web press where plates on different cylinders are arranged to make color imprints on the same page, it is obvious that the plates must be very carefully adjusted with respect to each other in order to insure accurate register of the several imprints.

10 In a copending application of Henry A. Wise Wood, Serial No. 535,165, filed May 5, 1931, there is disclosed a method of and machine for pre-registering a set of printing plates and notching them so that when applied to the cylinders of the printing press in cooperation with fixed reference points on said cylinders accurate register may be obtained without the necessity of using the printing press itself as a registering machine.

15 The present invention has for an object to provide for additional adjustment of a plate after it has been mounted on the cylinder so as to take care of variations in register that may occur during the running of the press. After the plates have been placed on a printing cylinder and the press has been operated there is a tendency for the plates to "grow" owing to the repeated passage of the plates through the impression point. Manifestly, if this "growing" of the plates is uniform or exactly alike in all the 20 plates printing a combination of colors there will be no disturbance of register. However, it sometimes happens that one plate is affected more than the rest and produces an offset in the final product.

25 It is an object of the present invention to provide means for effecting a slight adjustment of any of the plates on its printing cylinder, either longitudinally or circumferentially, or both, so as to restore the desired register.

30 Instead of mounting the plate directly on the cylinder it is within the purview of our invention to employ a plate carrier or "turtle" on which the plate may be securely clamped, the turtle being then mounted on the plate cylinder of the 35 press and clamped thereon in registered position.

35 We contemplate the use of plates which have been preregistered, as, for example, in the manner described in said copending application, Serial No. 535,165, and to this end our invention 40 comprises a turtle provided with fixed gauges, such, for example, as V blocks adapted to fit the notches cut in the plate by a preregistering machine, so as to insure the proper location of the plate on the turtle.

45 It is a further object of our invention to pro-

vide a plate cylinder with means for mounting a turtle thereon in a predetermined normal position and also to provide means for adjusting the turtle either longitudinally or circumferentially, or both, with respect to such normal position, so as to permit of readjusting the register destroyed by the action described above.

5 Other objects of our invention will appear in the following description of a preferred embodiment and thereafter the novelty and scope of the 10 invention will be pointed out in the claims.

In the accompanying drawings:

Figure 1 is a fragmental end view of a printing cylinder with our invention applied thereto;

Fig. 2 is a view in longitudinal section taken 15 on the line 2—2 of Fig. 1, showing a pair of printing plates and how each is clamped to a turtle;

Fig. 3 is a view in longitudinal section taken 20 on the line 3—3 of Fig. 1, showing means for clamping the turtles upon the cylinder;

Fig. 4 is a view in section taken on the line 25 4—4 of Fig. 1, showing means for shifting an outside turtle longitudinally of the cylinder;

Fig. 5 is a similar view in section taken on the line 5—5 of Fig. 1, showing means for shifting an inside turtle longitudinally;

Fig. 6 is a view in section taken on the line 30 6—6 of Fig. 1, showing means for shifting the turtles individually in circumferential direction; and

Fig. 7 is a fragmental plan view looking in the direction of the arrows 7—7 in Fig. 1, with certain parts of the printing plates and the turtles broken away to reveal details of the longitudinal 35 and circumferential adjusting means.

Our invention is shown in the drawings as applied to a printing cylinder 10 which is preferably long enough to carry four printing plates lengthwise on each diametric half of the cylinder, but only two plates and a fragment of a third are shown in the drawings. It will be understood that the outside and inside printing plates 12 and 12a adjacent one end of the cylinder are adjustable by mechanism operated at 40 said end, while the outside and inside plates adjacent the opposite end are adjustable by identical mechanism from said opposite end of the cylinder.

45 Each printing plate is mounted on a turtle of substantially semicylindrical form. Although the turtles are all of identical construction and hence are interchangeable, for convenience the one which carries the outside plate 12 is indicated by the reference numeral 14 and the one 50 55

which carries the inside plate 12a by the reference numeral 14a. The plates are clamped to the turtles by means of clips 15 which are slideable in T slots 16 formed in opposite ends of the turtle. 5
5 The clips are arranged in opposed pairs engaging opposite ends of the printing plate and each pair is moved into and out of clamping position by means of a rod 17 threaded into the clips with right and left hand threads respectively. Each 10 rod 17 is formed with a square socket 18 at each end adapted to receive a wrench with which the rod may be turned to tighten up the clips. As shown in Fig. 2 each clip is formed with a lip adapted to overlap the beveled arcuate edge of the 15 plate. It will be observed by an inspection of Fig. 1 that there are eight clips 15 at each end of each printing plate.

Before the plates are applied to the turtles they are brought to proper relative register by any 20 suitable means, such as the preregistering machine described in said copending application and in each plate a V shaped notch 19 is cut in each arcuate end of the plate. As shown, particularly in Figs. 6 and 7, each turtle is provided with a 25 pair of opposed V blocks 20 adapted to enter the notches 19 so as to locate the plate accurately on the turtle.

Each turtle is undercut at opposite ends thereof to form a bevelled rabbet 21 adapted to be engaged by four opposed pairs of clamps which are fitted to slide in T slots 22 formed in the cylinder 30. A pair of clamps are indicated at 23 and 24, in Fig. 3, for the outer turtle and are moved into and out of clamping position by a tubular clamping screw 25. This tubular screw has a shoulder 26 which bears against the outer end of the clamp 23 while a collar 27 bears against the inner end of said clamp and is fixed to the screw by a set screw 28. This serves to retain the clamp 23 35 against longitudinal displacement with respect to the screw but permits the latter to rotate for the purpose of drawing the opposite clamp 24 into or out of clamping position. To this end, the clamp 24 has a threaded engagement with the screw. 40 At its outer end the screw is provided with a squared head 30 to which a wrench may be applied to tighten the clamps upon the turtle.

The inside turtle 14a is similarly secured between four pairs of clamps 32 and 33. Passing 50 through each hollow screw 25 is a screw rod 34 provided at its outer end with a squared head 36. This rod has a reduced extension 37 which passes through the clamps 32 and 33. A shoulder 38 is formed at the junction of the extension with the 55 main body of the rod which bears against the outer end of the clamp 32. A collar 39 fixed upon the extension by a set screw 40, bears against the inner end of the clamp 32 to hold the latter against longitudinal displacement with respect to the rod, although the rod may freely turn with respect to the clamp. The free end of the extension 37 has threaded engagement with the clamp 33 so that by applying a wrench to the head 36 and turning the screw rod the clamps may be moved 60 into or out of clamping engagement with the turtle.

In order to center the turtle accurately with respect to the cylinder, each turtle is provided with a transverse slot 42 (Fig. 7) adapted to be 70 engaged by a tongue or pin 43 projecting from the slide 44 (Fig. 4) which is movable longitudinally of the cylinder in a recess 45 formed in the face of the cylinder. To adjust the slide longitudinally we provide a rod 46 which is fitted to 75 turn in a longitudinal bore in the cylinder and

which has threaded engagement with the slide 44. This rod is maintained against longitudinal displacement by a shouldered head 47 at its outer end and by an opposed collar 48 which bears against the outer end wall of the recess 45. The 5 collar is secured to the rod 46, at desired adjustment, by a set screw 49. Obviously, by turning the rod 46 the turtle and the printing plate it carries may be adjusted longitudinally.

As shown in Fig. 1, the rod 46 carries a calibrated disk 50 and there is a reference point 51 marked on the end of the cylinder so that the position of the turtle longitudinally of the cylinder may be adjusted to a normal position by turning the rod 46 until a zero point on the calibrated 15 disk registers with the reference point 51. When the turtle has to be adjusted out of normal position to take care of any displacement or "growing" of the plate carried thereby, the calibrations will afford a convenient means for determining how much the head 47 should be turned to restore the plate to proper registration in longitudinal direction.

A similar adjustment is provided for the inside printing plate 12a. In Fig. 1, I show the head 52 25 of a screw rod 53 for longitudinally adjusting the turtle 14a. The screw rod 53, as shown in Fig. 5, extends through a bore in the cylinder into a recess 54, similar to the recess 45, and has threaded engagement with a slide 55 which bears a pin 56 30 adapted to engage a transverse slot 57 in said inner turtle. The head 52 may also be provided with a calibrated disk 59 and the end of the cylinder with a reference mark 60. It will be observed that although the slots 42 and 57 are not 35 in alinement as the turtles are applied to the cylinder, nevertheless, they are symmetrically disposed with respect to the longitudinal center lines of the turtles, so that either turtle may be turned end for end to bring the slot therein into 40 position for engagement either by the pin 43 or by the pin 56.

In order to provide for circumferential adjustment of the turtles, each turtle is provided along its longitudinal center line with a pair of diagonally disposed slots 62 which are adapted to be engaged by pins projecting from a slide adjustable longitudinally in the cylinder. The slide which controls the circumferential adjustment of the outer turtle 14 is shown at 64 in Fig. 6 and carries pins 63 engaging slots 62. This slide 64 is 50 adjustable in a recess 65 formed in the cylinder and has threaded engagement with a tubular screw 66. The latter extends outwardly through a bore in the cylinder and is provided at its outer end with a squared head 68. This screw is held against longitudinal displacement with respect to the cylinder by engagement of the head 68 with the outer end of cylinder 10 and by an opposed collar 69 secured to the sleeve by set screw 70 60 and bearing against the outer wall of the recess 65.

The slide 72 which controls the position of the inner turtle 14a is similar in form to the slide 64 and bears pins 63a which engage the slots 62 of the inner turtle. The slide 72 has threaded engagement with a screw rod 73 which passes through the tubular screw 66 and terminates at its outer end in a square head 74. The rod 73 is prevented from longitudinal displacement with 70 respect to the cylinder by a collar 75 secured thereto by means of a set screw 76 and engaging the outer end of the recess 76 in which slide 72 is adjustable, the opposite end of this recess being engaged by the inner end of the rod 73.

As shown in Fig. 1, calibrations are marked on the end of the cylinder about the head 68 so as to show by reference to a pointer 77 on said head whether the pins 63 are in normal position for the outer turtle 14a and also to provide a gauge for circumferential adjustment of said turtle. A similar gauge for the pins 63a engaging the inside turtle 14a is provided by forming calibrations on the face of the head 68 and a pointer 78 on the head 74.

In operation, the printing plates are first pre-registered, and they are then properly located on the turtles by engagement of V blocks 28 with notches 19, after which they are securely clamped to the turtles by tightening the screw rods 17. The pins 43, 56, 63 and 63a are adjusted to normal position by adjusting the heads 47, 52, 68 and 74 all to zero position. The turtles are then mounted on the cylinder, being properly centered by said pins, after which the screw heads 30 and 36 are turned to clamp the turtles fast.

When it is desirable to shift any plate out of normal position, the turtle which carries it is unclamped by turning screw heads 39 or 36, as the case may be. Then if it be desired to shift the turtle longitudinally the rod 46 or the rod 53, as the case may be, is adjusted correspondingly. If, on the other hand, it be desired to adjust a turtle circumferentially, the tubular rod 67, or, rod 73, is adjusted. Owing to the inclination of the slots 62, longitudinal movement of the pins engaging them will result in circumferential movement of the turtle. It will be obvious that when a turtle is adjusted longitudinally by means of pin 43 or 56 it will be obliged to move circumferentially as well, owing to the engagement of pins 63 or 63a with its inclined slots 62, but after the longitudinal adjustment has been secured any circumferential displacement may be corrected by turning head 74 or 68, as the case may be.

The clamp screws 25 and 37 are somewhat loosely mounted longitudinally of the cylinder to permit of proper registration of the plate. As shown in Fig. 3, pins 79, 80 and 81 are provided in the floor of the T slot. These are so arranged that when the turtle 14 is unclamped, the clamped screw 30 will move the inner clamp 24 toward the right, as viewed in Fig. 3, until the pin 80 is engaged and thereafter the clamp 23 will be compelled to move outwardly, or, toward the left, until the pin 79 is encountered. The clamps are thus spread apart sufficiently to release the turtle and permit its removal from the cylinder. Similarly when the turtle 14a is unclamped the clamping screw 36 is operable to move the clamp 33 until it engages a pin 81 after which further turning of the clamping screw will move the clamp 32 toward the left until the turtle is released.

While we have described a preferred embodiment of our invention, it will be understood that this merely illustrates one form of our invention, to which we are not limited, and that we reserve the right to make various changes in form, construction and arrangement of parts without departing from the spirit and scope of the invention as pointed out in the following claims.

We claim:

1. The combination with a printing cylinder, of means for registering and clamping a printing plate relatively to said cylinder, said plate being formed with opposed registration notches, said means comprising a pair of opposed blocks mounted on the cylinder and adapted to enter

said notches to locate the position of the plate relatively to the cylinder, means for adjusting the blocks on the cylinder with respect to a predetermined normal position, and means for clamping the plate fast with respect to the cylinder in any position determined by said blocks.

2. The combination with a printing cylinder, of means for registering and clamping a printing plate relatively to said cylinder, said plate being formed with opposed registration notches, said means comprising a pair of opposed blocks mounted on the cylinder and adapted to enter said notches to locate the position of the plate relatively to the cylinder, means for adjusting the blocks on the cylinder, means for indicating the position of the blocks with respect to a predetermined normal position, and means for clamping the plate fast with respect to the cylinder in any position determined by said blocks.

3. The combination with a printing cylinder, of means for registering and clamping a printing plate, said plate being formed with opposed registration notches, said means comprising a pair of opposed blocks mounted on the cylinder and adapted to enter said notches to locate the position of the plate, means for shifting the blocks longitudinally of the cylinder, means for shifting the blocks circumferentially of the cylinder, means for indicating the position of the blocks with respect to a predetermined normal position, and means for clamping the plate fast with respect to the cylinder in any position determined by said blocks.

4. A registering and clamping mechanism for printing presses comprising a printing cylinder, a printing plate therefor, gauge means for locating said plate in predetermined normal position with respect to the cylinder, means for adjusting said plate longitudinally with respect to said normal position, means for adjusting the plate circumferentially with respect to said normal position, and clamping means for securing the plate with respect to the cylinder either in said normal position or in any of such adjusted positions.

5. A registering and clamping mechanism for printing presses comprising a printing cylinder, a printing plate therefor, gauge means for locating said plate in predetermined normal position with respect to the cylinder, means for adjusting the plate longitudinally with respect to said normal position, means for adjusting the plate circumferentially with respect to said normal position, clamping means for fixing the plate with respect to the cylinder either in said normal position or in any of such adjusted positions, and means for indicating the degree of any adjustment of the plate with respect to said normal position.

6. A registering and clamping mechanism for printing presses comprising a printing cylinder, a pair of printing plates adapted to be mounted end-to-end lengthwise with respect to the cylinder, gauge means for accurately locating each plate in predetermined normal position, means operable from one end of the cylinder for adjusting each plate individually in longitudinal direction with respect to said normal position, additional means also operable from the same end of the cylinder for adjusting each plate individually in circumferential direction with respect to said normal position, and means for clamping each plate fast with respect to the cylinder either in said normal position or in any of such adjusted positions.

7. A registering and clamping mechanism for printing presses comprising a printing cylinder, a pair of printing plates adapted to be mounted end-to-end lengthwise with respect to the cylinder, gauge means for accurately locating each plate in predetermined normal position, means operable from one end of the cylinder for adjusting each plate individually in longitudinal direction with respect to said normal position, 5 additional means also operable from the same end of the cylinder for adjusting each plate individually in circumferential direction with respect to said normal position, means for clamping each plate with respect to the cylinder either in said normal position or in any of such adjusted positions, and a gauge associated with each adjusting means for indicating the degree of adjustment of each plate.
8. A registering and clamping mechanism for printing presses comprising a printing cylinder, a turtle adapted to be mounted thereon and providing a support for a printing plate, means on the turtle for accurately locating the printing plate in predetermined position thereon, clamps adapted to secure the plate fast to the turtle in said position, cooperating means on the cylinder and turtle and adapted when in predetermined position to locate the turtle in a normal position on the cylinder, means for adjusting the cooperating means to shift the turtle longitudinally and circumferentially with respect to said position, and means for clamping the turtle fast to the cylinder either in said normal position or in the adjusted position.
9. A registering and clamping mechanism for printing presses comprising a printing cylinder, a turtle adapted to be mounted thereon and providing a support for a printing plate, means on the turtle for accurately locating the printing plate in predetermined position thereon, clamps adapted to secure the plate fast to the turtle in said position, cooperating means on the cylinder and turtle and adapted when in a predetermined position to locate the turtle in a normal position on the cylinder, means for adjusting certain of the cooperating means to shift the turtle longitudinally, means for adjusting other of the cooperating means to shift the turtle circumferentially with respect to said position, and means for clamping the turtle fast to the cylinder either in said normal position or in any such adjusted position.
10. A registering and clamping mechanism for printing presses comprising a printing cylinder, a turtle adapted to be mounted thereon and providing a support for a printing plate, means on the turtle for accurately locating the printing plate in predetermined position thereon, clamps adapted to secure the plate fast to the turtle in said position, cooperating means on the cylinder and turtle adapted when in predetermined normal position to locate the turtle in a normal position on the cylinder, means for adjusting certain of the cooperating means to shift the turtle longitudinally, means for adjusting other of the cooperating means to shift the turtle circumferentially with respect to said position, means for clamping the turtle fast to the cylinder either in said normal position or in any such adjusted position, and means for indicating the position of said cooperating means with respect to said predetermined normal position.
11. A registering and clamping mechanism for printing presses comprising a printing cylinder, a pair of turtles adapted to be mounted thereon end-to-end lengthwise of the cylinder, each turtle providing a support for a printing plate, means for locating and clamping the plate in a predetermined position on the turtle, cooperating means on the cylinder and each of the turtles for accurately locating each turtle in a predetermined normal position on the cylinder, means operable from one end of the cylinder for adjusting each turtle individually in longitudinal direction with respect to said normal position, 10 separate means also operable from one end of the cylinder for adjusting each turtle individually in circumferential direction with respect to said normal position, and means for clamping each turtle in said normal position and also in 15 any such adjusted position.
12. A registering and clamping mechanism for printing presses comprising a printing cylinder, a pair of turtles adapted to be mounted thereon end-to-end lengthwise of the cylinder, each turtle providing a support for a printing plate, means for locating and clamping the plate in a predetermined position on the turtle, cooperating means on the cylinder and each of the turtles for accurately locating each turtle in a predetermined normal position on the cylinder, means operable from one end of the cylinder for adjusting each turtle individually in longitudinal direction with respect to said normal position, 20 separate means also operable from one end of the cylinder for adjusting each turtle individually in circumferential direction with respect to said normal position, means for clamping each turtle in said normal position and also in any such adjusted position, and a gauge associated with each adjusting means for indicating the degree of adjustment of each turtle with respect to said normal position.
13. A registering and clamping mechanism for printing presses comprising a printing cylinder, a turtle adapted to be mounted thereon and providing a support for a printing plate, means for accurately locating and clamping the plate in predetermined position on the turtle, cooperating means on the cylinder and turtle comprising a pair of pin-and-slot connections therebetween for locating the turtle in a predetermined normal position on the cylinder, one of the slots being disposed transversely to the longitudinal extent of the cylinder and the other slot being disposed at an angle thereto, whereby upon relative longitudinal movement of the pin with the first named slot the turtle will be adjusted longitudinally and upon relative longitudinal movement of the other pin with said other slot the turtle will be moved circumferentially, means for effecting such relative movement of each pin-and-slot connection individually, and means for clamping the turtle to the cylinder at any adjustment of the pin-and-slot connections.
14. A registering and clamping mechanism for printing presses comprising a printing cylinder, a turtle adapted to be mounted thereon and providing a support for a printing plate, means for accurately locating and clamping the plate in predetermined position on the turtle, cooperating means on the cylinder and turtle comprising a pair of pin-and-slot connections therebetween for locating the turtle in a predetermined normal position on the cylinder, one of the slots being disposed transversely to the longitudinal extent of the cylinder and the other slot being disposed at an angle thereto, whereby upon relative movement of the pin with the first named slot the turtle will be adjusted lon-

- 5 longitudinally and upon relative movement of the other pin-and-slot the turtle will be moved circumferentially, means for effecting such relative movement of each pin-and-slot connection individually, means for clamping the turtle to the cylinder at any adjustment of the pin-and-slot connections, and gauge means for indicating a normal position of each pin-and-slot connection.
- 10 15. A registering and clamping mechanism for printing presses comprising a printing cylinder, a turtle adapted to be mounted thereon and providing a support for a printing plate, means on the turtle for accurately locating the plate in predetermined position thereon, clamps adapted to secure the plate fast to the turtle, the turtle being formed with a pair of slots, lugs mounted to slide in the cylinder and adapted to engage the slots respectively, means for individually adjusting each lug longitudinally in the cylinder, one of the slots being disposed transversely with respect to the direction of movement of the lugs and the other slot being disposed diagonally with respect to such direction of movement of the lugs whereby upon movement of the first lug the turtle will be adjusted longitudinally and upon movement of the second lug the turtle will be adjusted circumferentially, clamps adapted to secure the turtle fast to the cylinder at any adjusted position, and gauge means adapted to indicate a normal position of the lugs.
- 15 20 25 30 35 40 15. A registering and clamping mechanism for printing presses comprising a printing cylinder, an adjustable gauge adapted to locate a printing plate longitudinally with respect to the cylinder, a gauge adapted to adjust the plate circumferentially with respect to the cylinder, means for adjusting one of the gauges on the cylinder to move the plate axially, and means for adjusting the other gauge to move the plate circumferentially and axially, and clamping means for fixing the printing plate in any position determined by either gauge.
- 15 20 25 30 35 40 15. A registering and clamping mechanism for printing presses comprising a printing cylinder, an adjustable gauge adapted to locate a printing plate longitudinally with respect to the cylinder, a gauge adapted to adjust the plate circumferentially with respect to the cylinder, means for adjusting one of the gauges on the cylinder to move the plate axially, and means for adjusting the other gauge to move the plate circumferentially and axially, means for indicating the position of the gauges with respect to a predetermined normal position, and clamping means for fixing the plate in any normal position determined by the gauges.
16. A registering and clamping mechanism for printing presses comprising a printing cylinder, a turtle adapted to be mounted thereon and providing a support for a printing plate, means on the turtle for accurately locating the plate in predetermined position thereon, clamps adapted to secure the plate fast to the turtle, the turtle being formed with a pair of slots, lugs mounted to slide in the cylinder and adapted to engage the slots respectively, means for individually ad-
- justing each lug longitudinally in the cylinder, one of the slots being disposed transversely with respect to the direction of movement of the lugs and the other slot being disposed diagonally with respect to such direction of movement of the lugs whereby upon movement of the first lug the turtle will be adjusted longitudinally and upon movement of the second lug the turtle will be adjusted circumferentially, clamps adapted to secure the turtle fast to the cylinder at any adjusted position, and gauge means adapted to indicate a normal position of the lugs.
16. A registering and clamping mechanism for printing presses comprising a printing cylinder, an adjustable gauge adapted to locate a printing plate longitudinally with respect to the cylinder, a gauge adapted to adjust the plate circumferentially with respect to the cylinder, means for adjusting one of the gauges on the cylinder to move the plate axially, and means for adjusting the other gauge to move the plate circumferentially and axially, means for indicating the position of the gauges with respect to a predetermined normal position, and clamping means for fixing the plate in any normal position determined by the gauges.
